UNITED STATES PATENT OFFICE.

JAMES R. HOPKINS, OF VINE GROVE, KENTUCKY, ASSIGNOR OF ONE-HALF TO WILLIAM C. WOODS, OF VINE GROVE, KENTUCKY.

CURTAIN-STRETCHER.

1,255,010.

Specification of Letters Patent.

Patented Jan. 29, 1918.

Application filed August 29, 1916. Serial No. 117,554.

To all whom it may concern:

Be it known that I, JAMES R. HOPKINS, a citizen of the United States, residing at Vine Grove, in the county of Hardin and 5 State of Kentucky, have invented certain new and useful Improvements in Curtain-Stretchers, of which the following is a specification.

This invention relates to curtain stretchers, and has for its primary object to provide a simplified and improved device of this character which embodies means whereby curtains of various lengths and widths may be easily and quickly arranged within, 10 stretched and detached from the device, and which further embodies means for adequately stretching the curtain without danger of tearing the same.

A further object of the invention is to 20 provide a curtain stretcher of this character which is of simple and inexpensive construction, which is composed of but few readily assembled parts, all so constructed and arranged as to minimize the opportunity for 25 wear, breakage or derangement of the same, which is positive in operation and which may be taken apart and folded so as to occupy but a small amount of space when not in use.

With these objects in view, together with others which will appear as the description proceeds, the invention resides in the novel formation, combination and arrangement of parts, all as will be described more fully 35 hereinafter, illustrated in the drawings, and particularly pointed out in the claims.

The invention will be best understood with reference to the accompanying drawing, wherein:

40 Figure 1 is a top plan view, parts broken away, of a curtain stretcher, constructed in accordance with my invention;

Fig. 2 is a side elevation of the device shown in Fig. 1;

45 Fig. 3 is a bottom plan view of one end of the stretcher frame;

Fig. 4 is a detail perspective view of one of the sliding sleeves employed in carrying out the invention;

50 Fig. 5 is an enlarged sectional view taken upon the line 5—5 of Fig. 1;

Fig. 6 is a similar view taken on the line 6—6 of Fig. 1, and

Fig. 7 is a detail perspective view of one of the stretcher bar holding plates. 55

Referring now more particularly to the drawings, 8 indicates a pair of main bars, each of which is broken at a suitable point in its length and hinged as at 9 to permit of the same folding upon themselves. Slidably arranged upon each of the main bars 8 is a pair of sleeves 10, the latter snugly inclosing the main bars and being held in their different positions of adjustment by the set screws 11. Formed with each of the sliding sleeves 10 and in a plane slightly above the same is a loop portion 12, the opening of which is disposed at right angles to that of the sleeve portion to which it is attached. A guide flange 13 projects upwardly from 70 the sleeve 10 and is disposed in alinement with and in the same general direction as one edge of the loop portion 12.

Slidably arranged at their ends within the alined loop portions 12 upon the opposing 75 main bars 8 are transverse frame bars 14. Set screws 15 are threaded through the loop members 12 and are adapted to impinge the frame bars arranged therein to hold the same in various positions of adjustment. 80 The frame bars 14 and the main bars 8 may be graduated as shown, whereby the width and length required for the stretching of a certain fabric may be quickly and easily determined. By loosening the set 85 screws 11 and 15, it is obvious that the frame consisting of the main and frame bars 8 and 14 may be very easily and quickly expanded or contracted. When arranged the desired distance apart, the set screws may be tightened to maintain the bars in fixed position. 90

Carried by each of the main and frame bars is a stretcher bar 16. The stretcher bars supported by the end or frame bars 14 are of substantially the same dimension as 95 the latter and are held spaced from the inner longitudinal edges thereof by bracket members 17. The stretcher bars lie in the same plane with the frame bars 14, and rest upon the main or longitudinal bars 8. The 100 bracket 17 comprises a metallic plate having a downwardly and inwardly extending tongue 18 projecting from its inner longitudinal edge, the said tongue engaging beneath and supporting the stretcher bar 16. 105 Inwardly extending arms 19 also project

from the inner longitudinal edges of the plate 17 and engage over the top face of the adjacent stretcher bar. Screws or tacks may be driven through suitable openings 20 in 5 the tongue 18 to firmly secure the stretcher bar thereto.

The stretcher bars 16 carried by the longitudinal or main bars are secured upon the upper faces thereof, and lie in the same horizontal plane with the stretcher bars carried by the end or frame members 14. The longitudinally disposed stretcher bars are formed in sections as shown, to permit of the device being readily folded. It will be understood that the extremities of the sectional stretcher bars will abut when the main or longitudinal bars are extended or in operative position.

Each of the stretcher bars above described 20 is equipped with means for securing the edge of a curtain or other fabric thereto, and are rabbeted or cut away upon their inner edges and throughout the extent thereof as indicated at 21. The base portions of these 25 cut outs are grooved or channeled as at 22, the construction providing a shallow upwardly extending rib 23 at the outer part of the rabbeted portion and extending throughout the length of the stretcher bar. Projecting upwardly from the channels in 30 the said stretcher bars and inwardly from the ribs 23 thereof are pegs or pins 24, the latter being adapted to engage through the edge of a curtain fabric.

Associated with each of the stretcher bars 35 is a clamp member 25. The clamp members in the present instance comprise elongated plates substantially coextensive with the stretcher bars to which they are applied, and 40 project at one longitudinal edge outwardly over the rabbeted or cut away portion 21. The extended edges of the plates are bent downwardly to provide foot portions 27, the latter being bent inwardly at their lower 45 most ends as at 28 to present a substantially rounded edge. These rounded edges terminate in close proximity to the bottoms of the channels formed at the base of the cut out portions, and are disposed inwardly from 50 the pegs 24. As a means for securing the clamps 25 upon their respective clamp bars, bolts 29 are extended upwardly through the clamp bars and through laterally disposed elongated slots 30 in the clamp members. 55 The upper threaded extremities of the bolts 29 may be equipped with wing nuts 31, whereby the clamps may be adjusted toward and away from their clamp bars and also to permit of adjusting the clamps laterally of 60 the said bars. The bolts 29 extend through the longitudinal or main bars 8 and thence through the clamp bars and clamps, where-

by the said bolts bind the clamp bars to the longitudinal bars, and the clamps to the clamp bars.

In operation, the lateral and longitudinal bars of the frame are adjusted through their sliding sleeves and loop portions to the size proper for the accommodation of the fabric to be stretched. The set screws are then 70 tightened, whereupon the wing nuts 31 are loosened so that the edges of the fabric may be engaged over the pegs housed beneath the depending foot portions of the clamps. After the fabric is thus arranged within 75 the frame, the wing nuts are tightened, whereupon the clamps are forced downwardly until their rounded smooth portions engage with the fabric, and thus bind the edges of the same into the channel at the 80 bottom of the rabbeted portion. If desired, the fabric thus stretched may be further tensioned by moving the stretcher bars outwardly or inwardly, and it will be apparent that such movements or the contraction of 85 the fabric will be borne by the elongated foot portions of the clamps. Tearing out of the fabric edges is thus obviated.

While the above is a description of the preferred embodiment of the invention, it is 90 obvious that various changes in the minor details of construction and arrangement of parts may be resorted to without departing from the spirit of the invention or exceeding the scope of the claims.

What is claimed is:

1. In a device of the class described, a plurality of movable stretcher bars, each bar being provided with a longitudinally extending groove, a clamp on each bar, a foot portion on each clamp extending into the adjacent groove, and means for moving said foot portions laterally of said groove and toward and away from the bottoms thereof, substantially as described.

2. In a device of the class described, longitudinal and lateral main and frame bars adjustably secured to each other, stretcher bars secured to said lateral bars, a plate secured to each of said frame bars, a tongue projecting downwardly and forwardly from each plate, arms projecting from the ends of each plate and lying above said tongue, clamp bars carried by said plates and being supported between said arms and tongues, and means for securing fabrics to said clamping bars, substantially as described.

In testimony whereof I affix my signature in presence of two witnesses.

JAMES R. HOPKINS.
